UNITED STATES PATENT OFFICE.

WEBSTER C. ESTES, OF FLATBUSH, NEW YORK.

DESIGN FOR A BOX.

SPECIFICATION forming part of Design No. 21,289, dated January 12, 1892.

Application filed November 14, 1891. Serial No. 411,938. Term of patent 7 years.

To all whom it may concern:

Be it known that I, WEBSTER C. ESTES, a citizen of the United States, residing at Flatbush, in the county of Kings and State of New York, have invented a Design for a Wooden Box, of which the following is a specification.

The leading feature of this design is the plain bell-shaped cover with a rounded lower edge and a rib around the rim and the cylindrical box with ribs and an intermediate cove around the bottom.

In the drawings, Figure 1 is a vertical section, and Fig. 2 a plan view.

The general configuration of the box and cover is round. The cylindrical portion *a* has

the ribs *cd* and the intermediate cove around the lower end, and the cover is bell-shaped, with a plain surface terminating with a downwardly-rounded edge and a rib below the edge and around the rim, as at *f*.

I claim—

The design for the shape and configuration of the wooden box, substantially as described and represented.

Signed by me this 12th day of November, 1891.

WEBSTER C. ESTES.
